Primary Examiner — Katrina A Betton*(74) Attorney, Agent, or Firm* — Dale J. Ream**CLAIM**

The ornamental design for a portable vehicle covering device, as shown and described.

DESCRIPTION

FIG. 1 is a perspective view of a portable vehicle covering device showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

In the drawings, the broken lines showing a vehicle illustrate environment and form no part of the claimed design.
